UNITED STATES PATENT OFFICE.

GEORGE H. SHATTUCK, OF NEW YORK, N. Y.

DESIGN FOR A PEN-HOLDER BARREL.

SPECIFICATION forming part of Design No. 18,492, dated July 24, 1888.

Application filed May 3, 1888. Serial No. 272,719. Term of patent 14 years.

To all whom it may concern:

Be it known that I, GEORGE H. SHATTUCK, a citizen of the United States, residing in New York city, in the county and State of New York, have invented and produced a new and original Design for Pen-Holder Barrels, of which the following is a specification, reference being had to the accompanying drawings, forming a part thereof.

Figure 1 is a side elevation of my newly-designed pen-holder barrel, and Fig. 2 is an end view.

The leading features of my design consist in projections of rounded form extending in the same plane from the side of a barrel or body of cylindrical shape, one of the ends of the barrel having a rounded projection, as shown.

The barrel A is cylindrical in its general

form, and the ears B B', which project from the cylinder, have a rounded outline, and are both arranged in the same plane, as shown. One end of the cylinder has upon one side an elongation of a rounded form, as represented in the drawings.

I claim—

A design for a pen-holder barrel herein shown and described, the same consisting of a cylinder-barrel having a rounded elongation at one end and rounded lateral projections at the side, substantially as shown in the annexed drawings.

GEO. H. SHATTUCK.
